TESTING WELLS

Don H. Flickinger, Tulsa, Okla., assignor to Pan American Petroleum Corporation, Tulsa, Okla., a corporation of Delaware

Filed Dec. 5, 1960, Ser. No. 73,909

5 Claims. (Cl. 166—3)

This invention relates to testing wells. More specifically, it relates to the well testing method and apparatus in which a conduit is lowered into a well, a packer is set between the conduit and the well wall to isolate a zone of the well below the packer and fluids from the isolated zone are allowed to flow up inside the conduit.

A convenient form of well testing equipment uses a packer which can be set by hydraulic pressure. An example of such equipment is described in detail in U.S. Patent 2,611,437 Lynes. In the equipment described in the Lynes patent, pressure is applied through the conduit to inflate a packer or packers after which the conduit is manipulated by turning, raising or lowering, or a combination of motions to close the packer inflating ports and open one or more ports which connect the conduit and the zone to be tested.

The use of inflatable packers as just described offers a very advantageous system except for the necessity of removing the liquid normally used in the conduit to exert the pressure necessary to set the packers. This liquid must be removed to decrease the pressure on the zone to be tested so fluids can enter the conduit from this zone. Recently this difficulty has been partly solved by using a gas to actuate the packers. That is, the conduit and well testing equipment, including the packers, are run into the well empty. The gas under pressure is introduced into the top of the conduit from containers of compressed gas, by means of compressors or by use of liquefied gas. The gas pressure in the conduit is increased to a value sufficient to set the packers. After the packer inflation ports are closed, the pressure in the conduit is released by opening a valve at the surface to permit escape of the gas. Increasing the gas pressure in the conduit to the desired level has proved to be a time-consuming operation. In addition, the expense and inconvenience of transporting either large containers of compressed gas or a gas compressor to the well is an objectionable feature.

An object of this invention is to provide a method and apparatus for well testing in which the conduit and well testing equipment can be run empty and the hydraulically settable packer or packers can be actuated without the use of compressors, containers of compressed gas, or the like at the surface of the earth. Other objects will be apparent from the following description and claims.

In general, I accomplish the objects of my invention by the use of a gas-generating charge lowered into the well on a wire line or electric cable. The container of the charge is a pressure vessel which is locked in sealed engagement with the well testing equipment after the container reaches the desired location near the bottom of the conduit so that the gas which is generated exerts pressure only on the well testing equipment and a small volume of the conduit near the well testing equipment. After the high-pressure gas has expanded the packers, each packer is locked in expanded position. The gas-generating charge container can then be released and withdrawn after which the well testing procedure can be carried out as usual.

My apparatus and method will be better understood from a consideration of the drawing in which:

FIGURES 1A and 1B present a vertical view in cross-section of one embodiment of well testing equipment suitable for my purposes;

FIGURES 2A and 2B present a cross-sectional view of one form of a gas-generating equipment suitable for my

2

purposes together with associated means for locking the equipment in sealed engagement with the well testing equipment shown in FIGURES 1A and 1B;

FIGURE 3 is a view in vertical cross-section of another form of gas-generating equipment;

FIGURE 4 is a view in vertical cross-section of a mechanism for locking the equipment of FIGURE 3 in sealed engagement with the equipment shown in FIGURE 1.

Considering the figures in more detail, in FIGURES 1A and 1B, an outer sleeve or mandrel 10 carries packers 11. The ends of the packers are secured to sleeve 10 by clamps 12. An inner sleeve 13 is slidably mounted within outer sleeve 10. Sleeve 13 slides within sleeve 10 within limits imposed by flange 14 operating in chamber 15 which is an enlarged portion of outer sleeve 10. Upward motion of sleeve 13 is limited by flange 14 striking a retainer ring 16 and lower motion is limited by the bottom surface 17 of chamber 15. Flange 14 is prevented from turning in chamber 15 by extensions 18 sliding in grooves 19 in the wall of chamber 15. Inner sleeve 13 is supported by conduit 20 through connector 21. Conduit 20 is preferably drill pipe but may be tubing of steel or the like which is sufficiently thick-walled to withstand the pressure differentials involved. At the bottom of inner sleeve 13, ports 22 may be sealed by plug or go-devil 23 including retrieving head 24. Near the top of sleeve 13 is a relief valve 25 which prevents developing sufficient pressure in sleeve 13 to damage packers 11. Outer sleeve 10 includes ports or passages 30, communicating with the interior of packers 11 and ports or passages 31, communicating with any well zone isolated by the packers 11. Ports 32 in inner sleeve 13 are aligned with ports 30 in outer sleeve 10 when inner sleeve 13 is in its upper position with respect to sleeve 10. Ports 33 in inner sleeve 13 are aligned with ports 31 in outer sleeve 10 when inner sleeve 13 is at or near its lower position with respect to outer sleeve 10.

The equipment in FIGURES 1A and 1B is shown in a somewhat diagrammatic form. More detailed drawings of this type of equipment may be found in U.S. Patent 2,611,437 which was previously mentioned. Inflatable packers of still other designs can, of course, also be used. In addition, it is possible to use packers in which a sleeve of resilient packing material is squeezed between two rings, the compressive force being provided by hydraulic pressure acting on a piston connected to one ring and a cylinder connected to the other. A packer of this sort is shown in more detail in U.S. Patent 2,760,583, for example. Still other packers which can be set by the action of hydraulic pressure will occur to those skilled in the art. The inflatable packers are preferred, however, because of their simplicity.

The apparatus of FIGURES 2A and 2B is shown on a considerably larger scale than that of FIGURES 1A and 1B to permit a better showing of details. The entire apparatus of FIGURES 2A and 2B is designed to be lowered through the conduit 20 of FIGURE 1A. Gas-generating charge 40, preferably a slow-burning propellant, is enclosed in pressure chamber or container 41 which is lowered into the well or reinforced electric cable 42. An electric lead 43 in the cable passes through an insulated seal (not shown) and is attached to a blasting cap 44 in the end of explosive charge 40. The other lead 45 to the blasting cap can be grounded or can be connected to another lead in cable 42. A small orifice 39 is provided in the wall of container 41.

Mandrel 46 is attached to the bottom of container 41. A passage 47 is provided through the center of mandrel 46. Slips 51 are mounted on pistons 52 in the wall of mandrel 46. Fluid pressure inside passages 47 acts through ports 53 against pistons 52 to compress springs 54 against retainer rings 55 to cause outward motion of slips 51 from the center of mandrel 46. These slips are

designed to lock the gas-generating charge and associated equipment in conduit 20.

Attached to the bottom of slip mandrel 46 is packer mandrel 56. Packer 57 is mounted on mandrel 56. This packer is preferably of the downwardly-facing cup type. Below packer 57 expanding cone 58 is slidably mounted on mandrel 56. Sliding motion of cone 58 is limited by flange 59 on mandrel 56. The cone is normally held in retracted position, as shown in FIGURE 2B, by springs 60 acting against flange 59 and retainer ring 61. Ports 62 are provided through the wall of packer mandrel 56 below the base of cone 58. Passage 63 is provided through the center of mandrel 56 and is aligned with passage 47 through slips mandrel 46. Ports 62 thus expose the bottom of cone 58 to any pressure within passage 63. The base of cone 58 is surrounded by sleeve 64 which acts as a cylinder in which cone 58 can act as a piston when exposed to pressure in passage 63 acting through ports 62. The bottom of the annular space between mandrel 56 and sleeve 64 is sealed by a base element 66. This base 66 includes a passage 67 aligned with passage 63 in mandrel 56. The bottom of passage 67 is closed by a shear disc 68 which is held in place by cap 69.

In operation, the apparatus of FIGURES 2A and 2B, which may be termed the gas-generating equipment, is lowered through conduit 20 after the well testing equipment of FIGURES 1A and 1B has been run on conduit 20 to the desired level in the well. The gas-generating equipment is preferably run to a point as close as possible above the well testing equipment to avoid the need for filling a large volume of conduit 20 with compressed gas. When the gas-generating equipment reaches the desired level, an electric current is sent down conductor 43 to detonate blasting cap 44 and actuate gas-generating charge 40. The gases enter passages 47 and 63 in mandrels 46 and 56, respectively, locking the gas-generating equipment in sealed engagement with conduit 20 and, therefore, with the well testing equipment. Shear disc 68 holds the gases within the gas-generating equipment until the slips and packer are solidly set. When the pressure reaches some predetermined value, such as 1,000 pounds per square inch, disc 68 ruptures, allowing the gas to pass into conduit 20 and through ports 30 and 32 of the packers 11 which are expanded to isolate a desired zone of the well to be tested. If an excessive pressure develops, this is relieved through safety valve 25.

Packers 11 are sealed in expanded condition by lowering conduit 20. Contact of expanded packers 11 with the wall of the well presents downward motion of sleeve 10, so sleeve 13 moves downwardly with respect to sleeve 10. The gases within the gas-generating equipment and well testing equipment slowly leak out through orifice 39 to equalize pressures inside and outside of mandrels 46 and 56. When pressures approach being equalized across these mandrels, springs 54 withdraw slips 51 and spring 60 withdraws cone 58 permitting packer 57 to collapse. This allows withdrawing the generating equipment from the well. Testing of the well can then proceed by further lowering of conduit 20 to align ports 31 and 33. This permits fluids from the isolated zone of the well to flow into conduit 20 through which they can flow to the surface. If the zone has insufficient pressure to cause fluids to flow to the surface, a sample can be obtained by use of suitable apparatus such as a wire line bailer, for example.

After the well test, conduit 20 can be raised to realign ports 30 and 32 and permit packers 11 to collapse. The conduit and equipment can then be withdrawn from the well. If the conduit contains considerable liquid, it may be desirable to run a wire line fishing tool to engage fishing head 24 on go-devil 23 and remove it from the well. This opens ports 22 to permit pulling a dry string.

In most wells the gas-generating equipment shown in FIGURES 2A and 2B will be found to be completely

satisfactory. It is to be noted, however, that in my method the well testing equipment and conduit are run in substantially empty condition. Therefore, when the gas-generating charge is fired, the entire pressure required to expand the packers against the pressure of the well will be imposed upwardly against the packers and slips of the gas-generating equipment. In a deep well, this pressure may reach a value of 10,000 pounds per square inch or even more. The total force tending to blow the gas-generating equipment up the hole is the product of this pressure and the internal cross-sectional area of conduit 20, which may be considerable. In such extreme cases, it may be preferred to use a somewhat more positive means for locking the gas-generating equipment in sealed engagement with the well testing equipment. This is a critical requirement in my process. Such apparatus is shown in FIGURES 3 and 4.

In these figures, the apparatus of FIGURE 4 is a lower extension of the apparatus shown in FIGURE 3. As in FIGURES 2A and 2B, the gas-generating and the locking and sealing equipment are designed to be lowered through conduit 20 which is shown in FIGURE 4. In this case, however, conduit 20 includes, just above the well testing equipment, a seating nipple 70.

The apparatus of FIGURE 4 is simply an Otis removable mandrel assembly. In this apparatus dog-carrier 71 supports dogs 72 which latch in seating nipple 70. Extending through dog-carrier 71 is carrying mandrel 73 which supports locking mandrel 74 below the dogs. Below locking mandrel 74 is packing mandrel 75 with packing 76. The top portion of carrier mandrel 73 and dog-carrier 71 are modified as shown in FIGURE 3.

On the top of mandrel 73 is mounted a container 81 for a gas-generating charge 82. The top of container 81 is closed by cap 83 which includes a neck 84 and a flange 85 on the top of neck 84. Flange 85 is enclosed by, and slides in, a chamber 86 with a retainer ring 87. A flange extension 88 moves in groove 89 in the wall of chamber 86 to maintain pin 90 in alignment with port 91 in the top of check valve assembly 92.

The entire gas-generating assembly is supported by an electric cable 93 attached to ring 94 on chamber 86. Electric lead 95 passes through seal 96 in cap 83 to blasting cap 97 in gas-generating charge 82. The other electric lead to the blasting cap is grounded at 98 as shown, or may pass through a seal in cap 83 and be connected to another lead in cable 93. A shear disc 99 may be provided to seal the bottom port in chamber 81 and the passage in mandrel 73.

Spring arms 101 attached to the bottom of container 81 have end portions 102 bent to engage head 103 on dog-carrier 71. In one position of cams 104, ends 102 on arms 101 are held out so that they do not engage head 103. In the other position of cams 104, arms 101 are allowed to spring inwardly to a position where they do engage head 103. The position of cams 104 is controlled by gears 105 which are actuated by spring arms 106 attached to head 103. Spring arms 106 and gears 105 act as a ratchet mechanism so that on alternate strokes of mandrel 73 sliding up and down through dog-carrier 71 arms 101 are held away from head 103 or are allowed to spring in and engage head 103. Other ratchet and cam designs will occur to those skilled in the art.

In operation the gas-generating equipment of FIGURES 3 and 4 is lowered through conduit 20 with cams 104 in the positions shown in FIGURE 3 until packing 76 engages the top of the constricted portion of seating nipple 70. The packing is driven down into this constricted portion, permitting dogs 72 to enter the seating chamber. This driving action is accomplished by reciprocating chamber 86 against the top of flange 85. An upward pull on cable 93 then causes locking mandrel 74 to wedge dogs 72 firmly against the top shoulder of seating nipple 70. Dogs 72 and packing 76 thus lock the gas-generating equipment in sealed engagement with

the well testing equipment. Gas-generating charge 82 can then be actuated to set packers 11 of the well testing equipment as described previously in connection with the apparatus of FIGURE 2.

As soon as the packers of the well testing equipment are set, cable 93 can be slackened off to allow pin 90 to open check valve 92 and equalize the pressures above and below the gas-generating equipment. When these pressures are equalized, further reciprocating of chamber 86 on flange 85 drives locking mandrel 74 downwardly and releases dogs 72 so the gas-generating equipment can be withdrawn from the well.

When the packers were first driven down into seating nipple 70, carrying mandrel 73 moved downwardly with respect to dog-carrier 71, permitting spring arms 106 to pass up past gears 105. When an upward strain was imposed on cable 93 to bring locking mandrel 74 into engagement with dogs 72, cams 104 moved up with respect to spring arms 106, causing the ends of these arms to turn gears 105 and cams 104 one quarter of a turn. This allowed spring arms 101 to spring inwardly to a position where they would engage head 103 when lowered again. Thus, when carrier mandrel 73 was again driven down to release the dogs, bent ends 102 of arms 101 engaged head 103 permitting lifting the gas-generating assembly out of the well.

After the gas-generating equipment is removed, conduit 20 can be manipulated to align ports 31 and 33 to make the well test, as previously described. It will be apparent that still other designs of gas-generating equipment assemblies can be used if they are subject to being locked in sealed engagement with the well testing equipment as required in my method and then being released. A considerable variation is permissible in still other aspects of the apparatus and method.

For example, the preferred form of gas-generating charge is a stick molded of a solid rocket propellant such as ammonium nitrate in a matrix of rubber, cellulose acetate, or the like. Many such solid rocket propellants are now available having various burning rates. Still other explosives of widely different burning rates are described, for example, in U.S. Patent 2,740,478 Greene. The class may be conveniently defined as explosive propellants. Still other forms of gas-generating charges may be used. These may, for example, take the form of cylinders of highly compressed gases such as nitrogen. The compressed gases are particularly useful at shallow well depths where only moderate pressures are required. Still other gas-generating charges will occur to those skilled in the art.

Another permissible variation is to run the gas-generating assembly on an uninsulated wire line and drop a go-devil down the wire line to actuate the gas-generating charge. While a two-packer system has been shown and described, it will be apparent that the lower packer can be omitted if it is desired to test the entire portion of the well below the top packer.

My method has been described to this point as a way of testing a single zone in a well. Sometimes it is found that when ports 31 and 33 between the packers are aligned, little, if any, liquids enter the conduit from the zone isolated between the packers. In this case, it is frequently desirable to move the well testing equipment to a new level in the well and run another test. My apparatus and method are well adapted to such operations. It is only necessary to raise conduit 20 to close ports 31 and realign ports 30 and 32. This collapses the packers. The well testing equipment can then be moved to another level in the well where the packers are reset and a new well test is run in the same manner as the first test.

Sometimes a moderate amount of liquids may enter the conduit during the first test. Such liquids may be removed by use of a wire line bailer, for example, if desired. The second test can then be run as described

above. It should be noted, however, that it is not necessary to remove all the liquids from the bottom of the well testing equipment. In fact, I prefer to have sufficient liquid present in the equipment and conduit 20 to fill the packers plus enough to fill sleeve 13 at least to the level of ports 32. The reason is that liquids are relatively incompressible compared to gases. The gases from an explosive charge are hot. If the packer is inflated with the hot gases and the packer inflation ports are closed, the pressure inside the packers falls as the gases cool. If the hot gases are used to force a liquid into the packers, however, the pressure inside the packers does not drop after the inflation ports are sealed. In addition, a gas-inflated packer is somewhat more easily deformed than a liquid-filled packer due to the compressible nature of the gas. Therefore, even when a cylinder of compressed gas is used as the gas-generating charge and the gas is not hot, it is preferable to arrange for the packers to be actuated by a liquid driven by the gas, rather than actuating the packers by the gas itself.

It will be understood, in view of the desirability to have a limited amount of liquid in the equipment, that when reference is made to the conduit and equipment being substantially empty, it is contemplated that sufficient liquid may be present to fill the packers and sleeves to a point above the packer-inflating ports, or even to a point slightly above the entire well testing equipment. Likewise, when reference is made to removing excess liquid from the conduit after a first test and before a second test, it is also contemplated that sufficient liquid may be left to fill the equipment as first described.

It will be apparent from the above that I have provided a method and apparatus which accomplish the objects of my invention. By using a gas-generating charge which can be run on a cable, locked in sealed engagement with well testing equipment, and later can be released and withdrawn, it is possible to obtain all the benefits of running the well testing equipment substantially empty, without the necessity of large numbers of compressed gas cylinders or of gas compressing equipment at the surface to increase the pressure within the entire conduit leading to the well testing equipment.

I claim:

1. A method for testing a well comprising running into the well, on a conduit, testing equipment including at least one packer for isolating the zone in the well to be tested, said packer being of the type which is set by pressure in said conduit, said conduit and testing equipment being run substantially empty of liquids, lowering into said well through said conduit gas-generating apparatus including a gas-generating charge, locking said gas-generating apparatus in sealed engagement with said testing equipment, actuating said gas generating charge whereby gas pressure is developed which sets said packer, locking said packer in set condition, disengaging said gas-generating apparatus from said testing equipment, and opening a port in said equipment, said port connecting said conduit to the isolated zone of the well, and determining the amount and nature of fluids entering said conduit.
2. The method of claim 1 in which after said test has been made, said port is closed, the pressure is released to unseat said packer, liquid in the conduit from the first test is removed until the conduit is again substantially empty, said equipment is moved to a new location in said well, gas-generating apparatus including a new gas-generating charge is run, locked into sealed engagement with said well testing equipment, and said new gas-generating charge is actuated to generate gas pressure which sets said at least one packer, and said port is reopened to obtain a second test in said well without removing said equipment from said well.
3. The method of claim 1 in which said packer is of the hydraulically inflatable type and, before setting said packer, sufficient liquid is introduced into said well testing equipment to insure that said at least one packer is

filled with said liquid rather than with gas from said gas-generating charge.

4. Well testing apparatus comprising a fluid conduit, a tubular mandrel mounted on said conduit in alignment with said conduit, at least one fluid pressure expansible packer surrounding said mandrel, means for locking said packer in set condition, a gas-generating charge, a container for said charge, means for locking said container in sealed engagement with said conduit above said packer, means for actuating said charge, to discharge gas to expand said packer, means for releasing said means for locking said container in sealed engagement with said packer, a port in said mandrel below said packer, said port connecting the inside of said conduit to the isolated zone of the well below said packer, and means for opening and closing said port.

5. Well testing apparatus comprising an outer sleeve, inflatable packers surrounding said outer sleeve, said sleeve including a port opposite the interior of each of said packers and a port between said packers, an inner sleeve disposed within said outer sleeve, said inner sleeve being slidable within limits within said outer sleeve, said inner sleeve including ports capable of being aligned with said ports in said outer sleeve, opposite the interiors of said packers, and a port capable of being aligned with said port, in said outer sleeve, between said packers, said

5 ports in said inner sleeve being so arranged that the ports in the inner and outer sleeves between the packers are not in alignment when the ports in the inner and outer sleeves opposite the interiors of said packers are in alignment and vice versa, a conduit attached to said inner sleeve for lowering said sleeves and packers into said well, a gas-generating charge, a container for said charge, said container being capable of being lowered through said conduit, means for actuating said charge, means for locking said container in sealed engagement with said conduit above said sleeves, means for releasing said container, and means for lowering said charge and container through said conduit and removing said container from said conduit.
